ANIMAL TOY OR SIMILAR ARTICLE

Robert V. Longfield, 49 Glenbrook Mobile Estates, 4800
Auburn Folsom Road, and Belton C. Bibb, 7077 Pine
Gate Way, both of Loomis, Calif. 95650

Filed Sept. 2, 1970, Ser. No. 24,817

Term of patent 14 years

Int. Cl. D21—01

U.S. Cl. D34—15

Fig. 1

Fig. 2

Fig. 3

Fig. 4

Fig. 5

FIG. 1 is a top plan view of an animal toy or similar article, showing our new design;

FIG. 2 is an elevational view of one side, the opposite side being substantially similar in appearance;

FIG. 3 is a bottom plan view;

FIG. 4 is an elevational view of one end, the opposite end being substantially similar in appearance; and,

FIG. 5 is a sectional view, the compound planes of the section being indicated by the line 5—5 in FIG. 2 and illustrating the appearance of the pivot structure.

We claim:

The ornamental design for an animal toy or similar article, as shown and described.
